UNITED STATES PATENT OFFICE.

JOHN HAYES, OF BELLE VERNON, PENNSYLVANIA.

BABY CARRIAGE.

Application filed March 23, 1922. Serial No. 546,118.

To all whom it may concern:

Be it known that I, JOHN HAYES, a citizen of the United States, residing at Belle Vernon, in the county of Fayette and State of Pennsylvania, have invented certain new and useful Improvements in Baby Carriages; and I do hereby declare the following to be a full, clear, and exact description of the invention, such as will enable others skilled in the art to which it appertains to make and use the same.

The invention relates to improvements in baby carriages.

The object of the present invention is to improve the construction of baby carriages and to provide a simple, and comparatively inexpensive baby carriage having a swinging body adapted to be oscillated to enable the baby carriage to be used as a cradle for rocking or swinging a baby to sleep without removing it from the carriage and while the same is either indoors or outdoors.

A further object of the invention is to provide a baby carriage of this character having a hinged front and adapted to form a seat or extension of the bottom and operable by means adapted also to be used for oscillating the swinging body.

A further object of the invention is to provide a musical attachment adapted to be operated by the baby carriage when the same is pushed along and capable of being readily thrown into and out of operation so that the music may be played or not as desired.

With these and other objects in view the invention consists in the construction and novel combination and arrangement of parts hereinafter fully described, illustrated in the accompanying drawings and pointed out in the claim hereto appended, it being understood that various changes in the form, proportion and minor details of construction may be resorted to without departing from the spirit or sacrificing any of the advantages of the invention.

In the drawings—

Figure 1 is a side elevation of a baby carriage constructed in accordance with this invention,

Figure 2 is a central longitudinal sectional view of the same,

Figure 3 is a transverse sectional view taken in the plane of the rear axle and illus-

trating the construction of the clutch mechanism for throwing the musical attachment into and out of operation, 55

Figure 4 is a horizontal sectional view, parts being broken away to show clearly the construction of the musical attachment, 60

Figure 5 is an elevation of a musical toy embodying portions of the invention.

Like numerals of reference designate corresponding parts in all the figures of the drawings.

In the accompanying drawings in which is illustrated the preferred embodiment of the invention, 1 designates a substantially oblong casing mounted upon front and rear wheels 2 and 3 which are arranged on the terminal or spindle portions of front and rear axles 4 and 5. The axles are journaled in suitable bearing brackets 6 and 7 and are preferably supported by braces 8 and 9 but they may be mounted on the casing 1 in any other desired manner. The casing which constitutes a sounding board is provided with a series of longitudinal strings 10 preferably 24 in number but they may be more or less as will be readily understood. These 80 strings which are adapted to be tightened by keys 11 are struck by hammers 12 pivotally mounted at intermediate points at 13 on a transverse rod and provided at their front ends with heads for engaging the 85 strings and having rearwardly projecting arms 14 adapted to be engaged by pins 15 of a horizontal cylinder 16 mounted in suitable brackets 17 at the rear end of the casing 1. The cylinder is provided with a 90 central sprocket gear 18 which is connected by a sprocket chain 19 with a sprocket wheel 20 mounted on the rear axle at the center thereof.

In practice the sprocket gearing will be 95 housed within a suitable casing. The rear wheels are loose on the rear axle and one of the rear wheels is provided with a clutch section or base 21 which is adapted to be engaged by a slid able clutch member 22 100 consisting of a sleeve slidably interlocked with the axle and provided with an annular groove 23 and having teeth or projections 24 forming a clutch face to engage with the clutch face 21 of the rear wheel, whereby 105 when the slid able clutch member is interlocked with the wheel the latter will be secured to the axle and will cause a rotation

of the latter for imparting rotary movement to the cylinder of the music attachment.

The groove of the slidable clutch member 5 is engaged by a fork 25 connected by a rod 26 with an arm 27 of a shaft 28 adapted to be partially rotated to slide the sleeve or clutch section into and out of engagement with the wheel. The shaft 28 is mounted 10 on one of a pair of inclined handles 29 but it may be arranged in any other suitable manner and the said handles 29 are secured at their lower ends to the casing at opposite sides thereof and are supported by curved 15 braces 30 and are connected at their upper ends by a transverse rod 31 adapted to be grasped to push the baby carriage.

Mounted upon the horizontal casing at opposite sides thereof are leaf springs 32 20 of semi-elliptic form having forwardly and rearwardly extending arms or portions from the terminals of which a body 33 is suspended by front and rear side links 34. The body which is adapted to be oscillated to 25 swing or rock the baby to sleep is provided with a hinged front 35 adapted to be let down to form a seat or extension of the bottom of the body. Any desired form or style 30 of body may be employed and the front which is connected at the bottom by hinges 36 is raised and lowered by side rods 37 35 extending longitudinally of the sides of the body of the carriage and connected at their front ends to the front 35. The side rods 37 pass through guides 38 and are connected 40 at their rear ends by transverse rod 39 which is secured in an extended position in spaced 45 relation with the back of the baby carriage by a locking device composed of hinged rods 40 having a hinge connection at their outer 50 terminals with the body and with the rod 39 and provided at their adjacent ends with a joint 41 adapted to permit the rods to break and swing in one direction and forming a lock for holding them rigid against movement in the opposite direction. This will enable the hinged front of the body to be secured in its closed position but any other suitable means may of course be employed for holding the latter closed.

The rearwardly extending side rods and the transverse connecting rod 39 form a handle for enabling the body of the baby carriage to be oscillated to form a cradle for rocking or swinging the occupant to 55 sleep.

In practice the baby carriage will be equipped with a suitable brake for locking the same stationary to facilitate rocking or 60 swinging the body.

The baby carriage may be made in the form of a toy baby carriage and may be equipped with the musical attachment or the latter may be omitted if desired and in 65 Figure 5 of the drawings is illustrated a musical toy comprising a body 42 constituting a sounding board and supporting a series of longitudinal strings 43. The body is preferably in the form of a casing having 70 openings 44 through which project hammers 45. The hammers 12 and 45 are maintained in a predetermined position by coiled 75 springs 46 and 47 and the said hammers 45 are adapted to be operated by projections 48 of a wheel 49. The wheel 49 is mounted on a suitable shaft and is connected by 80 sprocket gearing 50 with a wheel 51 which supports the body 42. The pins and the 85 plugs may be arranged in any desired manner to play various tunes. The body 42 is provided at the back with a suitable handle 52 and the toy is adapted to be pushed along the ground or other supporting surface for rotating the wheel 49.

What is claimed is:—

A device of the class described including an open horizontal casing mounted on wheels, a body supported on said casing, strings contained within the casing and located under and protected by said body, a transverse rod on said casing, hammers pivoted on said rod and arranged to engage 90 the strings, a rotary cylinder carried by the casing substantially rearwardly of the body and provided with pins for operating the 95 hammers, and gearing for connecting the cylinder for driving movement from one of the wheels.

In testimony whereof I affix my signature.
JOHN HAYES.
